CLAIM

The ornamental design for over-bed rack, as shown and described.

DESCRIPTION

FIG. 1 is a first perspective view of the first embodiment of the over-bed rack,

FIG. 2 is an enlarged view of the detail “A,”

FIG. 3 is an enlarged view of the detail “B,”

FIG. 4 is a second perspective view of the first embodiment of the present invention,

FIG. 5 is a first perspective view of the second embodiment of the over-bed rack,

FIG. 6 is an enlarged view of the detail “C,”

FIG. 7 is an enlarged view of the detail “D,”; and,

FIG. 8 is a second perspective view of the second embodiment of the over-bed rack.

The broken lines in the drawings illustrate environment and form no part of the claimed design.

The dot-dot-dash lines define the bounds of the enlargement and form no part of the claimed design.
